UNITED STATES PATENT OFFICE.

ROBERT T. POLLOCK, OF BOSTON, MASSACHUSETTS, ASSIGNOR TO UNIVERSAL OIL PRODUCTS COMPANY, OF CHICAGO, ILLINOIS, A CORPORATION OF SOUTH DAKOTA.

PROCESS FOR FRACTIONALLY DISTILLING HYDROCARBONS.

Application filed April 11, 1921, Serial No. 460,527. Renewed September 27, 1926.

This invention relates to improvements in a process and apparatus for fractionally distilling hydrocarbon oils and refers more particularly to a process in which fractional distillation may be produced.

Among the salient objects of the invention are to provide a process in which the oil after vaporization is rectified in the dephlegmating column by being brought into heat conductive contact with distillate returned from the receiver whereby the distillate may be redistilled and the vapors produced therefrom condensed and collected separately from the vapors in the initial vaporizing chamber; to provide a process in which different distillates may be obtained from the oil undergoing treatment, and one wherein the boiling point of the distillate may be rendered very low, and to provide an apparatus for carrying out the process.

The single figure is a side elevational view with parts in section and parts broken away, of an apparatus suitable for carrying out my process.

The raw oil is introduced from any convenient source through the inlet pipe 1 and is charged by means of the pump 2 through a line 3 controlled by a valve 4 and introduced into the top of the dephlegmator 5 where it serves as a dephlegmating medium flowing in opposed direction to the vapors which rise in the dephlegmator and being brought in intimate contact therewith. The raw oil with its condensate content is drawn off through the line 6 controlled by valve 7 and introduced to the heating coils 8 through the line 9. The heating coils are mounted in the furnace 10 and are preferably heated by means of gas burners 11. The oil heated to cracking temperature is passed from the transfer line 12 to a vaporizing chamber 13 where the released vapors are taken off through the vapor line 14, controlled by a valve 15 and the residual product collecting therein drawn off as desired through the line 16 controlled by a valve 17. The partially spent gases from the furnace pass out through the flue 18 into the stack 19. In their travel, their heat may be utilized in connection with the vapor chamber or a second still 20 surrounding the dephlegmator. The vapors passing through the dephlegmator are subjected to the dephlegmating action of the raw oil as ex-

plained and the uncondensed portion will pass off through the line 21 to a water condenser 22 and be collected as distillate in the receiver 23. This receiver is equipped with a pressure relief pipe 24 controlled by a valve 25, liquid drawoff pipe 26 controlled by a valve 27 and a second drawoff pipe 28 regulated by a valve 29 which conducts a regulated portion of the distillate back to the still surrounding the dephlegmator and there introduces the heated distillate in the shell 20, permitting the distillate to completely surround the dephlegmator 5. This distillate being cooler than the vapors rising in the dephlegmator will assist the raw oil in rectifying or refluxing the vapors while at the same time, the heat from the vapors will be transferred to the returned distillate and the latter will be redistilled and a substantial portion of the distillate collected. The vaporized portion of the returned distillate introduced in the second still 20 will pass off through the line 30 to a second water condenser 31 from which it will flow as a liquid distillate into the receiver 32 through a line 33 controlled by a valve 34. The receiver 32 is equipped with a gas drawoff line 35 controlled by valve 36, said drawoff line communicating directly with a vacuum pump 37 whereby, if desired, a vacuum may be imposed on the second receiver, thereby increasing the distillation which may be produced in the second still 20. This vacuum may be imposed when desired in order to produce an increased amount of distillate or to regulate, to a certain extent, the dephlegmating action imposed on the vapors in the dephlegmator 5. The receiver 32 is also provided with the usual liquid draw off line as shown. The distillate maintained in the still 20 surrounding the dephlegmator may be permitted to volatilize rapidly by the imposition of a vacuum on the receiver 32.

The unvaporized portions of the distillate returned to the still 20 for the purpose of acquiring the heat from the vapors in the dephlegmator and at the same time, serving as the cooling medium the rectifying or dephlegmating column are drawn off through a line 38 controlled by a valve 39 and may be recharged through the pump 40 and line 41 controlled by a valve 42 to the charging line 9 by means of which the liquid distillate is

recharged to the heating zone for retreatment. On the other hand, if it is not desired to recharge this distillate to the heating zone, it may be drawn off through a line 43 controlled by a valve 44.

By introducing a mid-continent gas oil of approximately 32 degrees Baumé gravity, and heating the same to a temperature of from 700 to 800 degrees F. in the heating tubes and 10 permitting the same to vaporize in the vaporizing chamber, in thereafter subjecting the vapors to dephlegmating action, a good quality distillate of approximately 30% to 40% of the original charge may be procured 15 by collecting these dephlegmated vapors. By returning a portion of the distillate and redistillation of a substantial part, yields of higher quality distillate and having more uniform characteristics than that produced 20 in the primary receiver may be obtained.

I claim as my invention:

1. The process of distilling hydrocarbon oil, which comprises heating oil under cracking conditions of temperature and pressure 25 in a coil, in passing the heated oil to a vapor chamber where vaporization occurs, in introducing the vapors to a dephlegmator, in condensing and collecting the uncondensed vapors passing from said dephlegmator to provide a pressure distillate, in returning said 30 distillate to a zone of redistillation surrounding the dephlegmator and in which zone the distillate is heated by heat absorbed from the vapors passing through the dephlegmator 35 and from products of combustion from the cracking still, and in discharging for condensation and collection the vapors in said zone of redistillation.

2. The process of distilling hydrocarbon oil, which comprises heating oil under cracking conditions of temperature and pressure 40 in a coil, in passing the heated oil to a vapor chamber where vaporization occurs, in introducing the vapors to a dephlegmator, in condensing and collecting the uncondensed vapors passing from said dephlegmator to provide a pressure distillate, in returning said 45 distillate to a zone of redistillation surrounding the dephlegmator and in which zone the distillate is heated by heat absorbed from the vapors passing through the dephlegmator 50 and from products of combustion from the cracking still, in discharging for condensation 55 and collection the vapors in said zone of redistillation, and in maintaining said zone of redistillation under a pressure less than atmospheric.

3. A process for converting hydrocarbon oils, comprising subjecting the oil to conversion conditions of heat and pressure in a heating zone, passing the oil to a reacting zone wherein conversion occurs, passing the evolved vapors to a dephlegmator maintaining a superatmospheric pressure in the heating zone, reacting zone and dephlegmator, 60

in condensing and collecting the dephlegmated vapors, and re-distilling pressure distillate under a reduced pressure by the heat given up by the vapors passing through the dephlegmator. 70

4. A process for treating hydrocarbon oil, comprising passing the oil in a stream of restricted cross-sectional area through a heating zone wherein it is subjected to conversion conditions of temperature and pressure, discharging the heated oil from said stream into an enlarged reacting zone wherein conversion occurs, passing the evolved vapors to a dephlegmator wherein superatmospheric pressure is maintained, condensing and collecting so the dephlegmated vapors, redistilling pressure distillate under a reduced pressure by utilizing the heat given up by the vapors passing through the dephlegmator, and returning the unvaporized pressure distillate 85 to said stream for re-treatment.

5. A continuous process for treating hydrocarbon oil, comprising passing the oil in a stream of restricted cross-sectional area through a heating zone wherein it is highly 90 heated, transferring the highly heated oil from said stream into a reacting zone wherein conversion occurs, passing the evolved vapors to a dephlegmator, condensing and collecting the dephlegmated vapors, maintaining 95 a substantial superatmospheric pressure on the oil undergoing conversion and the vapors in said dephlegmator, and re-distilling pressure distillate under a reduced pressure by the utilization of the heat given up by the 100 vapors passing through the dephlegmator.

6. A continuous process for treating hydrocarbon oil, comprising passing the oil in a stream of restricted cross-sectional area through a coil in a heating zone wherein it 105 is highly heated, transferring the highly heated oil from said stream into a reacting zone wherein conversion occurs, passing the evolved vapors to a dephlegmator, condensing and collecting the dephlegmated vapors, maintaining a substantial superatmospheric pressure on the oil vapors in said dephlegmator re-distilling pressure distillate under a reduced pressure by the utilization of the 110 heat given up by the vapors passing through the dephlegmator, and returning the unvaporized pressure distillate to the inlet side of said coil to be passed therethrough with the charging stock for re-treatment. 115

7. A continuous process for treating hydrocarbon oil, comprising passing the oil in a stream of restricted cross-sectional area through a coil in a heating zone wherein it is highly heated, transferring the highly heated oil from said stream into a reacting zone 120 wherein conversion occurs, passing the evolved vapors to a dephlegmator, condensing and collecting the dephlegmated vapors, maintaining a substantial superatmospheric pressure on the oil undergoing conversion and 125 130

- the vapors in said dephlegmator, re-distilling pressure distillate under a reduced pressure by the utilization of the heat given up by the vapors passing through the dephlegmator, 5 and returning reflux condensate from the dephlegmator together with raw oil and unvaporized pressure distillate to the inlet side of said coil to be passed therethrough for re-treatment.
- 10 8. A continuous process for treating hydrocarbon oil, comprising passing the oil in a stream of restricted cross-sectional area through a coil in a heating zone wherein it is highly heated, discharging the highly heated oil into a reacting zone wherein conversion occurs, passing the evolved vapors to a dephlegmator maintained under superatmospheric pressure, condensing and collecting the dephlegmated vapors, re-distilling pressure distillate under a reduced pressure by utilizing the heat given up by the vapors passing through the dephlegmator, passing the unvaporized pressure distillate under a mechanical pressure to the inlet side of said coil
- to be passed therethrough together with the 25 charging stock for re-treatment.
9. A process for cracking hydrocarbon oils comprising subjecting the oil to cracking conditions of temperature and pressure in a heating zone, delivering the heated oil to a reaction zone, passing vapors evolved from the oil to a dephlegmating zone wherein the heavier fractions are condensed, forming reflux condensate to be recycled through the heating zone, subjecting vapors issuing from 30 said dephlegmating zone to final condensation, introducing regulated quantities of the resulting distillate to a vaporizing zone wherein substantial vaporization of such distillate is effected, returning reflux condensate 35 from said dephlegmating zone to said heating zone, and causing the same in passage from said dephlegmating zone to said heating zone to flow through a closed conduit disposed within said vaporizing zone in which substantial vaporization of said distillate is 40 45 effected.

ROBERT T. POLLOCK.
